UNITED STATES PATENT OFFICE.

ALFRED H. WITTSTEIN, OF CHICAGO, ILLINOIS, ASSIGNOR TO SCHRADER-WITTSTEIN COMPANY, OF CHICAGO, ILLINOIS, A CORPORATION OF ILLINOIS.

DESIGN FOR A SOLITAIRE-GEM SETTING.

SPECIFICATION forming part of Design No. 35,741, dated February 18, 1902.

Application filed August 7, 1901. Serial No. 71,273. Term of patent 7 years.

To all whom it may concern:

Be it known that I, ALFRED H. WITTSTEIN, a citizen of the United States, residing at Chicago, in the county of Cook and State of Illinois, have invented and produced a new and original Design for a Solitaire-Gem Setting, of which the following is a specification, reference being had to the accompanying drawings, forming a part thereof.

10 Figure 1 is a view in side elevation of a solitaire-gem setting of my new and original design; Fig. 2, a plan view thereof, and Fig. 3 a vertical section taken as indicated at line 3 of Fig. 2.

15 As shown in the drawings, the leading or material feature of my design consists of a rim *a* and open-work *A*, supporting the same and having prongs *a'* projecting above said rim, said rim and prongs comprising the bezel.

20 Minor features of my design are the dished form of the open-work *A*, the perforations *a²*, having curved lower walls and portions of their

upper walls formed by the rim *a*, the perforations or cuts *a³* at the upper portions of the standards *a⁴* of the open-work, the beads *a⁵* upon said standards, and the supporting-base *a⁶*, comprising the frustum of a hollow cone.

It is apparent that this design is applicable to solitaire-settings on finger-rings, shirt-studs, ear-rings, scarf-pins, and other like articles of adornment.

Having described my invention, what I claim as new, and desire to secure by Letters Patent, is—

The design for a solitaire-setting for gems, as herein shown and described.

In testimony whereof I have signed my name to this specification in the presence of two subscribing witnesses.

ALFRED H. WITTSTEIN.
